PAPER CREPING MACHINE

Peter J. Christman, Green Bay, Wis.

Application November 3, 1938, Serial No. 238,695

3 Claims. (Cl. 154—30)

This invention relates to a paper creping machine and method. The invention, however, is applicable to other uses.

An object of the invention is to provide extremely simple mechanism and method which is sturdy and inexpensive to manufacture and which effectively crepes paper as it is fed through the machine. A further object is to provide a method and means whereby paper is longitudinally creped in an accurate and uniform manner. 10 A further object is to provide a simple means and method whereby a paper strip after being slightly moistened is uniformly engaged throughout by spaced members which grip the paper and draw it together to form longitudinal creping thereof as the paper is advanced. Other specific objects and advantages will appear as the specification proceeds.

The invention is illustrated in a preferred embodiment, by the accompanying drawings, in which—

Figure 1 is a plan view of mechanism embodying my invention; Fig. 2, a side view in elevation thereof; Fig. 3, a detail sectional view, the section being taken as indicated at line 3 of Fig. 4; Fig. 4, a broken enlarged detail plan view of a portion of the spring mechanism; and Fig. 5, a broken plan view of a portion of the creped paper emerging from the machine.

30 In the illustration given, A designates a frame; B, chain mechanism; and C, spring members carried by said chain mechanism.

The frame A may be of any suitable construction. In the illustration given, it comprises standards which support bearings 10 for lower shafts 11 and 12 and upper bearings 13 for shafts 14 and 15. The upper shaft 15 is provided at one end with a drive wheel or drum 16 adapted to receive a belt from any suitable power source (not shown). Each of the shafts 11, 12, 14 and 15 are provided at their ends with sprocket wheels 17, the sprockets of which engage the conveyor chains of the mechanism B.

45 The mechanism B comprises upper link chains 18 and 19 and lower link chains 20. Each of the links of the chains is provided with an integral inward extension strap 21 which is perforated to receive the hook end 22 of one of the springs 23 comprising spring mechanism C.

50 The spring mechanism C consists of a number of coil springs 23 each provided with hooks 22 engaging the perforated straps 21 of the link chains. The coil springs 23 are preferably of equal length, but are stretched under the arrangement of the link chains shown. It will be

observed that the shafts 11 and 14 are considerably longer than the shafts 12 and 15 so that the sprocket wheels carried by the shafts 11 and 14 are spaced much more widely apart than the sprocket wheels carried by shafts 12 and 15. 5 Thus, those springs which are carried by the link chains adjacent the shafts 11 and 14 are considerably stretched while the springs near the shafts 12 and 15 are contracted to a much greater extent.

10 In order to permit free operation of the shafts 11, 14, 12 and 15, universal joints 24 are interposed, as shown in Fig. 1.

It will also be observed from the showing in Fig. 2 that the individual links of the superposed 15 chains are staggered with respect to each other. That is, for example, the straps 21 of the link chain 20 are spaced between the straps 21 of the link chain 20 directly above. Since the springs 23 are carried by the straps, the springs of the 20 lower chain are staggered with respect to the springs of the upper chain, as illustrated more clearly in Fig. 3.

In the drawings, the paper sheet fed to the machine is designated by the letter D. 25

Operation

In the operation of the method and mechanism, a strip of paper D which is to be creped is fed between the springs 23 of the two endless belts or chains, as shown more clearly in Figs. 2 and 3. Before being fed, or as it is being fed, the paper is slightly moistened to render it more pliable or resilient and to enable the paper to be engaged by the uniformly spaced convolutions or rounds of the springs 23. As the strip enters, it engages the spring convolutions which are relatively widely stretched apart. As the paper advances, the springs progressively contract and the individual convolutions of the spring grip the paper and draw it together so as to crepe the paper longitudinally. The longitudinal folding or creping is quite uniform because of the action of the individual spaced rounds of the spring which grip the moistened paper and uniformly contract or narrow the small portion of the paper engaged by the individual round. Because of the action of the great number of convolutions or rings of the springs and because of the resiliency 30 of the paper induced by the moistening, there is found to be no tearing of the paper but a uniform contracting thereof throughout its entire width. There is no tendency for the paper to slip between the springs, but, on the other hand, 35

the contracting of the paper is progressive and simultaneous with the contracting of the springs.

While I have described springs as being employed and prefer them because of their simple construction and inexpensive character, it will be understood that in place of the springs, individual ring mechanism may be employed together with other means for progressively bringing together the separate rings to narrow the paper.

5 By employing springs, however, I find that a very uniform stretching occurs with uniform spacing of the individual rings so that excellent results are obtained. At the same time, should one of the springs become broken or set in an 10 extended position, the ring can be readily removed and replaced at very slight expense. Thus, in the operation of the machine, should one of the operating ring structures become injured or inoperative, it is not necessary to throw away the entire spring belt, but repair or 15 substitution can be made readily with respect to the one element at very slight cost. Further, should one of the springs be found to contract with less facility and in uniform relation to the others, 20 this spring can be removed and replaced without affecting the remainder of the spring belt.

25 The mechanism is extremely simple, extremely easy to repair and maintained in operation, and accurate and effective in reducing the width 30 of paper and creping it.

The foregoing detailed description has been given for clearness of understanding only, and no unnecessary limitations should be understood therefrom, but the appended claims should be 35 construed as broadly as permissible, in view of the prior art.

I claim:

1. In creping apparatus, a frame, a pair of endless belts arranged one above the other, 40 means carried by said frame for supporting said belts so that the inner portions of the belts are in adjacent relation and adapted to receive therebetween the paper strip to be creped, said

belts each comprising separate coil springs which are stretched at one end of the frame and progressively contracted until they reach the other end of the frame, the springs of one belt being in staggered relation with respect to the springs 5 of the other belt.

2. In creping apparatus, a frame, drive shafts mounted in said frame, sprocket wheels carried by the ends of said shafts, chains engaging the sprockets of said wheels, one chain being above 10 the other at each side of the frame and the shafts at one end of the frame being longer than the shafts at the other end of the frame, coil springs carried by said chains being thus stretched at the end of the frame where the shafts are longer and 15 being contracted toward the end of the frame where the shafts are shorter, the innermost portion of said springs being brought into adjacent relation and being adapted to receive therebetween a paper strip, and means for driving one 20 of said shafts.

3. In creping apparatus, a frame, a pair of shafts at each end of the frame supported in superposed relation, the shafts at one end of the frame being longer than the shafts at the 25 other end, sprocket wheels carried by said shafts, universal joints in said shafts, endless chains engaging said sprockets and supported one over the other at each side of the frame, the links of said chains being equipped with spring-engaging projections, coil springs engaging said projections and extending across said frame so as to form a spring belt in which the coils are expanded at the end of the frame where the shafts are longer and relatively contracted at the end of the frame 35 where the shafts are shorter, the springs of one belt being in staggered relation to the springs of the belt thereabove and the adjacent inner portions of said spring belts providing between them a tortuous path for receiving paper to be 40 creped.

PETER J. CHRISTMAN.
